Charles Novak

BY

Marvin D. Alair

ATTORNEY

UNITED STATES PATENT OFFICE.

CHARLES NOVAK, OF DAVIDSONVILLE, MARYLAND.

AUXILIARY PROPELLER.

Application filed April 3, 1925. Serial No. 20,363.

To all whom it may concern:

Be it known that I, CHARLES NOVAK, a citizen of United States, residing at Davidsonville, in the county of Anne Arundel 5 and State of Maryland, have invented certain new and useful Improvements in Auxiliary Propellers, of which the following is a specification.

This invention relates to improvements in 10 driving means for motor propelled flying machines and has as one of its objects to provide a pair of propellers arranged in the manner of side wheelers to augment the propulsion of the vehicle to which they are 15 attached.

It is a further feature to utilize the spent, 20 exhaust gases of the motor to drive the auxiliary propellers, conserving their force and at the same time acting to muffle and minimize the exhaust in an effective manner.

Another purpose is in the provision of a 25 combined muffling and auxiliary driving device, inexpensive to construct, easy to install and effective in operation.

These several important aims and objects 30 are attained by the novel construction, combination and arrangement of parts, herein-after described and shown in the accompanying drawing, forming an essential portion of this disclosure, and in which:—

Figure 1 is a partial front elevational, 35 partial sectional view of an embodiment of the invention as fully assembled ready for operation.

Figure 2 is an end view of the same.

Figure 3 is a transverse sectional view

taken on line 3—3 of Figure 1.

The embodiment of the invention as shown 40 is composed of base brackets 10 to be secured on fuselage or frame of the vehicle, preferably near the rear.

A pair of heads 11 form the ends of a 45 cylindrical casing 12 fixed on the base, and journalled axially of the casing, in packed bearings 13, is a shaft 14 extending equally out at each end.

Mounted midway on the shaft, within the 50 casing is a drum 15 having a plurality of longitudinally extending vanes 16 arranged in uniform spaced relation on its periphery, the outer edges of the blades clearing the interior of the casing as the drum revolves.

At the rear of the casing, centrally thereof, is attached a flattened relatively wide 55 mouthed inlet nozzle 17, its outer tangen-

tially disposed end being contracted and adapted to be engaged with an exhaust pipe of the vehicle motor in a manner which will be understood.

Similarly at the front is an exhaust spout 60 18 directed as may be desired to discharge into the atmosphere freely.

It will now be seen that the motor exhaust 65 will enter the casing, impinge upon the vanes and cause the drum and shaft to rotate, the gases being eventually discharged after having performed their work, and it will also be understood that the casing and vanes act efficiently in muffling the sound normally produced by the exhaust. 70

Secured on the extending ends of the 75 shaft 14 are hubs 19 to which are rigidly attached a plurality of resilient blades 20, curved throughout their length in the direction of rotation as shown, these blades acting in the manner of paddle wheels assisting in 80 the propulsion of the vehicle, being auxiliary and supplementary to the main driving propellers.

Thus the device is driven by otherwise 85 lost energy and without creating back pressure if properly designed, besides acting as a muffler for the exhaust, the power of which is absorbed and utilized to the fullest extent possible.

Although the foregoing is generally descriptive of the invention, minor changes in form, proportion and even details of construction may be made without deviating 90 from the general scope of the appended claim.

Having thus described my invention and set forth the manner of its construction and operation, what I claim as new and desire to secure by Letters Patent, is:—

A device of the kind described comprising supports, a cylindrical casing having closed ends mounted on the supports, a shaft journalled in the casing ends, a drum on said shaft, said drum having a plurality 95 of spaced vanes, means for conducting exhaust gases into said casing to impinge upon the drum vanes to cause the drum to rotate, a vent for the spent gases, hubs fixed on the extending ends of the shaft, and a 100 plurality of curved spring blades fixed to the hubs in spaced relation.

In witness whereof I have affixed my signature.

CHARLES NOVAK.
